UNITED STATES PATENT OFFICE

CHARLES W. LINFESTY, OF HIGHLAND, CALIFORNIA, ASSIGNOR TO STEBLER PARKER CO., OF RIVERSIDE, CALIFORNIA, A CORPORATION OF CALIFORNIA

ROLLER CLEANING AND OILING DEVICE FOR DRIERS

Application filed April 18, 1928. Serial No. 270,999.

This invention relates to fruit driers, and more especially to that type of fruit drier adapted to treat citrus fruits, in which the fruit is carried upon a conveyer. These conveyers are usually made up of a plurality of rollers connected by a flexible coupling such as chains, or their equivalent.

It is to be observed that one of the difficulties encountered with the type of conveyer described, is that the oils and other substances which issue from the fruits as they are being treated, collect upon the rollers, and necessitate shutting down the machine more or less frequently for the purpose of cleansing the rollers.

The general object of the invention is the provision of a mechanical device adapted to facilitate the operation of cleaning and oiling the rollers of the conveyers of the general character described.

It is a further object of this invention to produce a cleansing and oiling device such as referred to above, which is simple in its construction and efficient in its operation, so that the length of time that the drier is shut down for the purpose of cleansing the rollers, is materially shorter than when the rollers have to be cleaned manually.

The invention possesses other objects and features of advantage, some of which, with the foregoing, will be set forth in the following description of the preferred form of the invention which is illustrated in the drawings accompanying and forming part of the specification. It is to be understood that I do not limit myself to the showing made by the said drawings and description, as I may adopt variations of the preferred form within the scope of my invention as set forth in the claims. The accompanying drawings illustrate a type of the invention in which the cleaning brushes may be controlled at will to bring them into operation when desired.

Referring to the drawings:

Figure 1 is a top plan view of a citrus fruit drier embodying my invention applied thereto, parts being broken away to better reveal the operative parts of my invention.

Fig. 2 is a side elevation of the drier of

Fig. 1. The cleansing and oiling device is shown in operative position.

Fig. 3 is a vertical sectional view taken upon the line 3—3 of Fig. 1, and showing the cleansing and oiling device elevated from 55

Broadly considered, the cleaning and oiling device of the present invention comprises one or more rotary brushes adapted to be raised or lowered at will to disengage or engage the rollers of a roller conveyer, as they move past the brushes. The brushes are preferably mounted on a swinging frame. Means are provided for rotating the brushes to effectually remove collected particles from the roller; and means are also provided for spraying liquid upon the brushes so as to facilitate the cleansing operation.

Another movable brush is mounted so that it can be brought into engagement with the 70 rollers to apply oil thereto; and means are provided for keeping this second brush moistened with a cleaning liquid or oil.

In greater detail, the cleansing and oiling apparatus is shown mounted upon a conventional citrus fruit drier which comprises a supporting structure or fixed frame 10 which carries an endless belt 11; this belt is usually made up of a plurality of freely rotating rollers 12 interconnected by chains 13 or their 80 equivalent. The arrow 14 of Fig. 2 indicates the direction of travel of the belt 11 to conduct oranges 16 or other fruits through the drier while they are being subjected to heat or other desired treatment. One of the principal difficulties encountered in the drying of citrus fruits, results from the fact that as the fruit is being subjected to heat, oils issue from the fruit and deposit upon the rollers, necessitating the frequent shutting down of the entire machine to remove the collected oil which collects in the form of a gummy substance over the surface conveyer, and in the present instance on the rollers 12. The removal of this gummed oil and particles of broken fruit is a primary object of my invention.

The belt 11 passes over a roller 17 and back through the drier upon another supporting structure or guide 18, and as the belt 11 passes 100

over the roller 17, the fruit 16 drops into a chute 19 which conducts the fruit around the vertical portion of the belt 11 and deposits it upon the belt upon that portion of the belt which is supported upon the guide structure 18 so that the fruit may travel back to the front of the drier during the process of being treated.

The formation of the above mentioned parts is merely conventional, and no claim is made to the novelty of the arrangement of these parts. My invention lies in the construction and arrangement of elements that co-operate to make the improved cleaning and oiling device adapted to operate upon such a conveyer.

The cleaning apparatus may be mounted in any suitable way to enable it to engage the conveyer. In the present instance it is preferably located in contact with or near the inner face of the conveyer so that the brushes can engage one side of the conveyer, while the other side of the conveyer is guided positively past and in contact with the brushes. In the present instance I provide a plurality of brackets 21, 22 and 23, depending from the supporting structure 10. The brackets 21 and 22 support a swinging frame 24 through the expedient of links 26, each of which is pivoted at one end to the frame 24 and at the other end to one end of a swinging arm 27 which is pivoted intermediate its ends to one of the brackets 21 or 22. A counterweight 28 is preferably adjustable upon the other end of each of the arms 27, with the result that the frame 24 is a floating frame and may be lowered or raised optionally, that is, at will, and may be stably retained in either a raised or lowered position.

A plurality of roller brushes 31, 32, and 33 are mounted for rotation upon the frame 24; they extend transversely to the conveyer and are provided with sprockets 34, 36, and 37, respectively, at one end, and the brushes 31 and 32 with sprockets 38 and 39 at the other end. The sprockets 38 and 39 at one end of the swinging frame are operatively connected by a chain 41, and the sprockets 36 and 37 by a chain 42, with the result that all three brushes are connected for rotation together, preferably in a common direction.

Another chain 43 for driving the brushes, is carried by the sprocket 34, and a sprocket 44 mounted to rotate on a fixed axis on the frame 10 is connected to a beveled gear 46 enmeshed with a gear 47. The gear 47 is carried by a shaft 48 which may or may not be one of the main power shafts of the drier, according to the requirements of the particular case. Hence it will be seen that when the shaft 48 is rotated, the gear 47 drives the gear 46 and sprocket 44, which, through the chain 43 drives the sprocket 34, and with it the rotary brush 31. However, since the brushes 32 and 33 are connected to

the brush 31, these brushes also will be rotated.

The frame is preferably formed with a hood 51 disposed over the brushes 31, 32, and 33, upon the frame 24; and a foraminated pipe 52 is disposed within the hood 51 in position to spray the brushes with liquid. The end of the pipe 52 extends through the side of the hood 51, and has a flexible conduit 53 connected thereto to supply the pipe 51 with water under pressure, or any other desired liquid. A tray 54 having a drain pipe 56 is disposed below the lower framework 18, in position to collect the liquid as it drops from the brushes 31, 32, and 33, through the belt 11.

The second framework 61 is also in the form of a swinging frame and may be similarly supported upon the brackets 22 and 23 by means of links 62, each of which is pivoted at one end to the frame 61, and at the other end to one end of a swinging arm 63. Each of the swinging arms 63 is pivoted at a point intermediate its ends to one of the brackets 22 or 23, and has a counterweight 64 adjustable upon its other end.

The frame 61 carries a flat brush 66 composed of bristles 67 carried by a back 68 which is provided with marginal flanges 69 extending upward therefrom so that the back 68 is in the form of a tray. A reservoir 71 is disposed above the back 68, and a discharge pipe 72 controlled by a valve 73, leads from the reservoir 71 to a point closely above the back 68 of the brush 66.

Means are provided for permitting oil to seep through the back 68 to the bristles 67. This may be done either by providing the back 68 with a plurality of perforations, or by permitting the bristles 67 to extend clear through the back 68 so that any oil contained within the tray-like back, may seep between the bristles to their lower ends.

When not in use the brush frames are supported by removable pins 23a and 26a on the horizontal arms of brackets 23 and 26 (see Fig. 3).

I will now describe the operation of my improved cleansing and oiling apparatus. When the rollers 12 have become so clogged as to require cleansing, the fruit 16 is run completely off the belt 11, and the pins 23a and 26a are then removed. This permits the brush frames to descend by gravity and rest yieldingly on the conveyer. The chain 43 is then placed in position upon the sprockets 34 and 44. Then by rotating the shaft 48, all three of the brushes may be rotated as above described. Water under pressure is then supplied to the pipe 52 so that the brushes are sprayed as they rotate. The belt 11 is then started in motion so that the rollers 12 pass beneath the rotating brushes to be effectually cleansed thereby. The tray 54 and waste pipe 56 serve to dispose of any

- surplus water and the foreign substances removed from the rollers. This is continued as long as is necessary to remove all collected oils and particles of foreign matter, after which the water is shut off and the chain 43 removed. The frame 24 is then elevated to withdraw it from the conveyer, and the frame 61 lowered into its operating position, in which the bristles 67 engage the rollers 12.
10. The bristles 12 are saturated with oil supplied to them from the reservoir 71, so that as the rollers 12 pass therebeneath, they are oiled and kept in perfect condition.

It is obvious that by adjusting the position of the counter-weights 28 and 64 the pressure of the brushes against the conveyer can be regulated.

I claim:

1. In a fruit drier including a conveyer comprising a plurality of parallel rollers, a swinging frame movably mounted adjacent said conveyer, a plurality of rotary brushes journaled upon said frame with their axes extending substantially parallel with said rollers, means for rotating said brushes, means for supplying liquid to said brushes, and means for moving said frame up or down to bring the brushes into or out of engagement with said rollers, at will, as they move past the same.

2. In a fruit drier including a conveyer comprising a plurality of rollers, a vertically movable frame mounted adjacent said conveyer, a rotary brush journaled upon said frame, means for rotating said brush, means for supplying liquid to said brush, means operable at will for moving said frame to bring the brush into or out of engagement with said rollers as they move therewith, and counterweights operatively connected to said frame to retain the brush either in engaging or disengaging position.

3. In a fruit drier including a conveyer comprising a plurality of rollers, a rotary brush arranged above said conveyer, means for rotating said brush, a second brush arranged adjacent said conveyer, means operable at will for moving each of said brushes into or out of engagement with the rollers as they move past the same, and means for feeding oil to said second mentioned brush.

4. In a fruit drier including a conveyer comprising a plurality of rollers, a rotary brush arranged above said conveyer, means for rotating said brush, a second brush arranged adjacent said conveyer, means operable at will for moving each of said brushes into or out of engagement with the rollers as they move past the same, counterweights operatively connected to each of said brushes to retain them in elevated or lowered position, and means for feeding oil to said second mentioned brush.

5. In a fruit drier including a conveyer comprising a plurality of rollers, a rotary

brush arranged above said conveyer, means for rotating said brush, a second brush arranged adjacent said conveyer, means operable at will moving each of said brushes into or out of engagement with the rollers as they move past the same, counterweights operatively connected to each of said brushes to retain them in elevated or lowered position, a foraminated pipe arranged adjacent said first mentioned brush to spray liquid thereupon, means for feeding water under pressure to said pipe, and means for feeding oil to said second mentioned brush.

6. In a fruit drier including a conveyer comprising a plurality of rollers, a rotary brush arranged above said conveyer, means for rotating said brush, a porous flat-backed brush arranged adjacent said conveyer, marginal flanges extending upwards from the back of said flat brush, means operable at will for moving each of said brushes into or out of engagement with the rollers as they move past the same, counterweights operatively connected to each of said brushes to retain them in elevated or lowered position, and means for feeding oil to said second mentioned brush.

7. In a fruit drier including a conveyer comprising a plurality of rollers, a rotary brush arranged above said conveyer, means for rotating said brush, a second brush mounted adjacent said conveyer, means operable at will for moving each of said brushes into or out of engagement with the rollers as they move past the same, counterweights operatively connected to each of said brushes to retain them in elevated or lowered position, a foraminated pipe arranged adjacent said first mentioned brush to spray liquid thereupon, means for feeding water under pressure to said pipe, a hood arranged over said rotary brush, a draining pan arranged under said rotary brush, and means for feeding oil to said second mentioned brush.

8. In a fruit drier including a conveyer, a porous flat-backed brush arranged adjacent said conveyer, marginal flanges extending upwards from the back of said brush, means for optionally moving said brush into or out of engagement with said conveyer, and means for feeding oil to the back of said brush.

9. In a fruit drier including a conveyer, a porous flat-backed brush arranged adjacent said conveyer, marginal flanges extending upwards from the back of said brush, means for optionally moving said brush into or out of engagement with said conveyer, counterweights operatively connected to said brush to retain it in adjusted position, and means for feeding oil to the back of said brush.

10. In a fruit drier having an endless conveyer with a plurality of transverse rollers, the combination of a rotary brush located on the inner side of said conveyer, a second rotary brush located on the inner side of said

conveyer, means for supporting said brushes for rotation on axes extending transversely to the endless conveyer, means for guiding the conveyer adjacent the said brushes so as to bring the rollers into contact with the brushes as they pass the same, means for driving the brushes, and means associated with the brushes for supplying liquid to the same.

11. In a fruit drier having an endless conveyer, the combination of a supporting frame, a swinging frame mounted on the supporting frame to swing toward or from the conveyer, a plurality of rotary brushes mounted on the swinging frame, a shaft mounted on the supporting frame, a belt connection from the said shaft to drive one of said brushes located at one end of said swinging frame, and a driving connection between the brushes located at the other end of the swinging frame.

20 In testimony whereof I have signed my name to this specification.

CHARLES W. LINFESTY.
